UNITED STATES PATENT OFFICE

FERDINAND S. BARBIERS, OF LANCASTER, OHIO, ASSIGNOR TO THE HOCKING GLASS COMPANY, OF LANCASTER, OHIO, A CORPORATION OF OHIO

DESIGN FOR A JAR

Application filed December 28, 1931. Serial No. 42,260. Term of patent 14 years.

To all whom it may concern:

Be it known that I, FERDINAND S. BARBIERS, a subject of the King of Belgium, residing at Lancaster, in the county of Fairfield and State of Ohio, have invented a new, original, and ornamental Design for a Jar, of which the following is a specification, reference being had to the accompanying drawing, forming part hereof.

The drawing, which is a perspective view, illustrates my design embodied in a glass jar.

I claim:—

The ornamental design for a jar, substantially as illustrated.

FERDINAND S. BARBIERS.
